ELECTRIC IRON HAVING A SUPPORTING MECHANISM

Benjamin Cooper, New York, N. Y., and Albert F. Hohmann, Teaneck, N. J.; said Hohmann assignor to said Cooper

Application April 28, 1947, Serial No. 744,304

2 Claims. (Cl. 38—79)

1

This invention relates to electric irons and the like in combination with retractable supporting means therefore.

An object of this invention is to provide in combination with an electric iron or the like, improved retractable means for supporting the iron on a surface so that its heating surface is out of contact with said surface when the iron is not in use.

Still another object of this invention is to provide in a device of the character described, improved retractable support means which may be readily moved into supporting or non-supporting positions.

Yet another object of this invention is to provide in a device of the character described, retractable support means which is pivotally mounted on the device in a manner which permits movement of the support means with a minimum amount of effort.

Still another object of this invention is to provide in a device of the character described, pivoted supporting means mounted on either side of the device and having means resiliently connected with said supporting means which urges the movement of said supporting means into operative or inoperative positions by movement of the device while holding same by its handle, with respect to a supporting surface.

Yet another object of this invention is to provide in a device of the character described, pivoted supporting means mounted on the device in such a manner as to be readily rotated into supporting position by movement of the device itself into a predetermined position with respect to a base surface. The supporting means may be retracted into a non-supporting position by manipulating the device into another predetermined position with respect to said base surface.

Yet another object of this invention is to provide a compact and rugged ironing device in combination with retractable supporting means therefore which shall be relatively inexpensive to manufacture, sure and positive in operation and practical and efficient to a high degree in use.

Other objects of this invention will be in part be obvious and in part hereinafter pointed out.

The invention accordingly consists in the features of construction, combinations of elements, and arrangement of parts which will be exemplified in the construction hereinafter described, and of which the scope of application will be indicated in the following claims.

2

In the accompanying drawing, in which is shown various possible illustrative embodiments of the invention,

Fig. 1 is a front elevational view of an iron embodying the invention and showing it in its supported position;

Fig. 2 is a front elevational view of iron in its unsupported position with parts cut away to show the support actuating mechanism;

Fig. 3 is a cross-sectional view taken on line 3—3 of Fig. 2.

Fig. 4 is a cross-sectional view taken on the line 4—4 of Fig. 2 but showing the supporting legs in a projected position and

Fig. 5 is a front elevational view of the details of the leg support actuating mechanism showing the leg support in its projected position.

Referring now in detail to the drawing, 10 designates an iron embodying the invention. The 20 same comprises a casing 11 which contains the usual heating element not shown, a sole plate 12 which is heated by the heating element and is secured to the lower portion of the casing, a top plate 13 secured to the upper portion of the casing and a handle 14 secured to the upper face of the top plate 13.

The casing 11 comprises an upwardly inclined top wall 15 of conventional triangular shape, from which a pair of side walls 16 30 extend downwardly and outwardly toward the sole plate 12. The walls 16 converge towards each other at their fore portions to form the apex portion 16a of the iron. The walls 16 are formed with openings 16b for the purpose herein- 35 after described. A rear wall 17 extends downwardly and is inclined outwardly from the top wall 15 and interconnects the side walls 16. The sole plate 12 which is generally triangular in shape and comprises side edges 18 and a rear edge 19 is secured to the bottom portion of the casing 11 in a manner well known in the art. The rear edge 19 of the sole plate 12 is spaced from the rear wall 17 of casing 11, thereby forming an opening 20 of generally rectangular shape.

40 Secured to a forward portion of the inner surface of the wall 15 of the casing by rivets, welding or the like and extending towards the side walls 16 is a bracket 21. The same comprises a web 22 contacting the wall 15 and outwardly and 45 downwardly inclined flanges 23, 23a which are spaced from and substantially parallel to the adjacent side walls 16 of the casing. The flanges 23, 23a are formed with through openings 24 aligned with openings 16b in the walls 16, for the purpose herein- 50 after described. Secured to a rear portion

of the under side of wall 15 and parallel to the bracket 21, is a bracket 25 which comprises a web 26 and depending flanges 27 which are formed with aligned openings 28. Mounted in the openings 28 is a transverse pivot pin 29 extending parallel to the top wall 15 of the casing and formed with headed end portions 29a to retain the pin against longitudinal movement. Secured on the pivot pin 29, exteriorly of the flanges 27, is a pivoted member 30 which comprises a rear wall 31 extending parallel to the pivot pin 29 and at right angles thereto a pair of parallel arms 32 formed with aligned openings 32a for receiving the pin 29. The arms 32 extend rearwardly towards the rear wall 17 of the casing 11. 15 Secured on the wall 31 and member 30 is a substantially U-shaped member 34. The member 34 comprises a wall 35 which is substantially coextensive with wall 31 of member 30 and is secured thereto by means of rivets, welding or the like. The member 34 further comprises a pair of parallel lever arms 36 extending at right angles from wall 35 towards the bracket 21. The end portions of arms 36 are formed with teeth 37 for the purpose hereinafter described.

Mounted in the opening 24 of flange 23 of bracket 21 and in the opening 16b of the adjacent wall 16 is a transverse pivot pin 38. Secured on the pin 38 and lying between the flange 23 and the wall 16 is a helical gear 39 which meshes with the teeth 37 on the adjacent arm 36 of member 34. The outer end of pivot pin 38 extends through the wall 16 and is formed with a reduced end portion 39 to which is received a supporting leg 40. The supporting leg 40 comprises an upper portion 41 formed with an opening 42 to receive the reduced end portion 39 of pin 38. Extending from upper portion 41 of arm 40 is an outwardly curved and offset portion 42 which is adapted to clear the edge 18 of sole plate 12 in spaced relationship thereto when in the position shown in Fig. 4. The length of arm 40 is such as to raise the sole plate 12 with respect to an ironing base surface 40a when the arms 36 are extended in the position shown in Figs. 1 and 4.

Mounted in the opening 24 of flange 23a and the opening 16b of adjacent wall 16, is a transverse pivot pin 43. Mounted on the pivot pin 43 and lying between the flange 23a and the wall 16 is a helical gear 39 similar to that previously described and which also meshes with the teeth 37 on the other arm 36 of member 34. The outer end of pin 43 extends through the wall 16 and has mounted thereon a supporting arm 40 similar to that previously described. The inner end of pin 43 extends through the opening in flange 23a and is provided with a collar 44 which spaces a circular disk 45 mounted on the pin 43, from the inner side of the flange 23a. The disk 45 has a part of its circumferential portion formed with a peripheral notch 46 which provides shoulder portions 47, 48 on either end thereof. The shoulders 47 and 48 are adapted to contact the side portions of web 22 of bracket 21 upon rotational movement of the disk 45 in clockwise and counterclockwise directions, respectively. The disk 45 is provided with an anchor post 49 secured to a peripheral outer portion adjacent the shoulder 48. The wall 35 of member 34 is provided with a hook 50. A coiled tension spring 51

has one end secured to the hook 50 and the other end secured on anchor post 49.

When using the iron the supporting legs 40 are in their retracted position lying along the side walls 16 as shown in Fig. 2. When it is desired to raise the heated sole plate 12 out of contact with the ironing surface 40a the iron is tilted while holding the handle 14 in the usual manner, using the rear edge 19 of the sole plate 12 as a fulcrum thereby bringing the apex portion 16a upwardly and simultaneously bringing the rear portions 33 of the pivoted member 30 into contact with the ironing surface 40a. Continued tilting movement of the iron causes the portions 33 of the arms 32 to press against the surface 40a thereby causing the pivoted member 30 to rotate about the pivot pin 29 in a clockwise direction, which in turn causes the teeth 37 on arms 36 to rotate the gears 39 in a counterclockwise direction. The movement of the gears 39 as indicated, rotates the associated supporting legs 40 also in a counterclockwise direction towards other supporting positions as shown in Figs. 1 and 4. It will be apparent from a consideration of Figs. 2 and 5, that as soon as the arms 36 have caused the gears 39 to rotate to a position which brings the anchor post 49 on the associated disk 45 to a point slightly above the axis of the inner end of pivot pin 43, the tension of spring 51 will cause accelerated rotational movement of the supporting legs 40 in a counterclockwise direction to their final operative position. The final position of the arms 36 is determined by the stop action of shoulder 48 on disk 45 as it bears against the edge of web 22 of bracket 21. In this position the iron is tilted back so that it is supported with respect to the surface 40a by the end portion 33 of arms 32, the rear edge 19 of the sole plate 12 and the arms 40 extending substantially at right angles to the walls 16 of the casing.

When it is desired to retract the legs 40 to such a position as to permit the normal use of the iron, it is only necessary to tilt the iron forward, using the end portions of the legs 40 as a fulcrum, until the legs pass through a position vertical with respect to the ironing surface 40a. The iron is then pressed in a direction towards the ironing surface 40a which initiates rotational movement of the pivoted legs 40 in a clockwise direction about pivot pins 38, 43. Continued movement of the legs 40 will bring the gears 39 and the disk 45 into a position wherein the anchor post 49 is below the axis of the pivot 43. At this point, the tension of spring 51 will accelerate the movement of the gears 39 and the associated legs 40 until the shoulder 47 on the disk 45 abuts the edge of the web 22 of bracket 21. Simultaneously, the movement of the legs 40 causes the counterclockwise movement of the arms 36 through the gears 39 and the engaging teeth 37 on arms 36, thereby pivoting the arms 32 about pin 29 to bring the end portions 33 of the arms 32 into their original position as shown in Fig. 2.

The use of the helical gears 39 on the inclined pivot pins 38, 43 permits proper engagement of the lever arms 36 therewith during the pivoted movement of the lever arms.

It will be apparent that the movement of positioning legs 40 from their non-supporting to supporting positions and vice versa may be accomplished with one hand holding the iron in the usual manner and requires a minimum amount of effort inasmuch as the spring 51 is adapted to cause a major portion of the necessary rotational movement of the legs.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described our invention, we claim as new and desire to secure by Letters Patent:

1. An iron comprising a casing, said casing comprising outwardly inclined side walls, a top wall and a rear wall, a sole plate on the bottom portion of said casing, the said sole plate terminating short of said rear wall thereby providing an opening between said rear wall and an edge of said sole plate, a flanged bracket seamed to the inner surface of said top wall, the flanges of said bracket extending in parallel, spaced arrangement to said side walls, an inwardly and downwardly inclined pivot pin mounted on each of said flanges and said adjacent side walls, said pins projecting through said side walls, supporting legs secured to the projecting portions of said pins, and disposed outside of said casing, helical gear means mounted on each of said pins between said flanges and said side walls, a pair of levers fixed to each other and pivotally mounted within said casing, one end portion of each of said levers being formed with gear means meshing with an adjacent helical gear, the other ends of said levers being formed with end portions projecting through said opening.

2. A device of the character described comprising a casing, said casing comprising a pair of side walls and a bottom wall, a supporting leg pivotally mounted on each of said side walls, and 5 adapted in one position to maintain said device in a tilted position with respect to a base surface, means within said casing for causing said supporting legs to rotate towards and away from said position, said means comprising a rotatable disk 10 on a pivotal portion of one of said supporting legs, stop means on said disk to limit rotation of said disk through a predetermined angle, and spring means fixed at one end within the said casing and secured at its other end to said disk whereby initial rotational movement of said disk on either side of a line connecting said fixed point and the axis of rotation of said disk will impart continued rotational movement of said disk towards the limits of movement of said disk.
